(57) CLAIM

The ornamental design for a garment, as shown and described.

DESCRIPTION

FIG. 1 is a front perspective view of a garment showing our design;

FIG. 2 is a front view thereof;

FIG. 3 is a first side view thereof; and,

FIG. 4 is a second side view thereof.

The long-and-short broken lines immediately adjacent shaded areas form an unclaimed boundary, and form no part of the claim.

The even-length broken lines are directed to environment, represent unclaimed subject matter, and form no part of the claimed design.

The contrast in shading represents a contrast in appearance only and does not represent any particular color, material, texture, or finish.
